UNITED STATES PATENT OFFICE.

FRANK O. HELLSTROM, OF BISMARCK, NORTH DAKOTA, ASSIGNOR TO AMERICAN
SAFETY STEEL RAIL CO., OF BISMARCK, NORTH DAKOTA.

RAILROAD-RAIL.

1,109,922.

Specification of Letters Patent. Patented Sept. 8, 1914.

Application filed December 15, 1913. Serial No. 806,895.

To all whom it may concern:

Be it known that I, FRANK O. HELLSTROM, a citizen of the United States, residing at Bismarck, in the county of Burleigh and 5 State of North Dakota, have invented a new and useful Railroad-Rail, of which the following is a specification.

This invention relates to railroad rails, its object being to provide a rail or rail section 10 made up of a reversible body and holding members combined therewith and extending throughout the length of the rail, these members extending across the meeting ends of the bodies so as thus to avoid the necessity of 15 utilizing fish plates, tie plates, bolts or other similar devices.

A further object is to provide a rail of this character the body and holding members of which have interfitting portions 20 whereby longitudinal creeping of the body relative to the holding members is prevented.

A further object is to provide holding members which bear upwardly against the lower surfaces of the upper head of the body, thus to reinforce the head and transmit the thrust therefrom to the bases of the holding members.

Another object is to provide holding members having means integral therewith for engaging and biting into a tie, thereby to form means for binding and locking the parts of the rail together automatically and at the same time prevent the rail from 35 spreading or slipping.

A further object is to provide means of this character designed to reduce to the minimum the number of spikes or other fastening devices used in connection with the rail.

40 A further object is to provide a continuous sectional rail by so arranging the parts of the rail as to cause them to form lapped joints.

A still further object is to provide a rail made up of separate sections whereby the said sections can be made of different compositions.

With the foregoing and other objects in view which will appear as the description 50 proceeds, the invention resides in the combination and arrangement of parts and in the details of construction hereinafter described and claimed, it being understood that changes in the precise embodiment of the invention herein disclosed, can be made

within the scope of what is claimed, without departing from the spirit of the invention.

In the accompanying drawings the preferred form of the invention has been shown. 60

In said drawings:—Figure 1 is a vertical transverse section through a rail embodying the present improvements. Fig. 2 is a side elevation of the rail on a reduced scale, the manner in which the holding member 65 extends past the ends of the meeting blades, being shown.

Referring to the figures by characters of reference 1 designates the web of the rail, the same constituting a connection between 70 two opposed similar heads 2 and 3, either of these heads being adapted to lie uppermost while the other head constitutes a base for engaging a seat 4 made up of base plates 5 extending longitudinally under and laterally beyond the body and provided on their lower faces with longitudinal ribs 6 which serve both to reinforce the base plates and to engage the ties T on which the plates are mounted. Each base plate has an upwardly 80 extending longitudinal flange 7 adapted to fit snugly against the side of the lower head of the body, the upper portion of the flange being inclined inwardly, as at 8, so as to extend upwardly under and into contact with 85 the upper head of the body. The surface of the upper head is formed at desired intervals with teeth or ribs 9 extending transversely thereof and the corresponding faces of the lower head are similarly provided 90 with teeth or ribs 9. The upper edges of the inclined portions 8 are toothed or serrated, as shown at 10 so as to engage the teeth or ribs 9 and thus prevent the body from shifting longitudinally independently 95 of the plates 5 and their flanges 7.

It will be noted that those portions of the base plates 5 and flanges 7 contacted by the lower head of the body are spaced to fit snugly against the head so that the 100 two holding members made up of the plates 5 and their flanges thus will grip tightly upon the body when the parts are properly assembled.

The base plates can be secured to the tie 105 in any desired manner, either by means of spikes 11, or bolts or screws 12, and it will be noted that the ribs 6, by extending into the tie, relieve the fastening spikes or bolts 11 or 12 of lateral strains to which they 110

might otherwise be subjected. These ribs also coöperate with the ties to bind and lock the parts of the rail together and to prevent the rail from slipping or spreading.

- 5 When the upper or active head of the body becomes worn to an undesirable extent, the body can be reversed or inverted so that the head which had previously been lowermost, is thus brought into position for engagement, but the wheels of the cars traveling on the rails. It will be noted, furthermore, that the reinforcing ribs 6 are disposed in line with the thrust exerted downward from the active or upper head 10 of the body so that the device is thus materially strengthened and better able to withstand the strains to which it is subjected while in use.

As shown in Fig. 2 the holding members made up of the plates 5 and their flanges 7 extend longitudinally and continuously and reinforce and support the entire body of the rail and are so arranged as to extend past the meeting ends of the body so that 20 it becomes unnecessary to use fish plates, tie plates, bolts or other means of fastening.

All of the parts making up the complete rail can be rolled readily.

It will be seen that by making the rail 30 of separate parts, the body portion of the rail can be made of a metal differing in grade from that of which the holding members are formed.

It will be noted that the down thrust of 35 the rail body upon the holding members is such as to bind said holding members upon the body and at the same time maintain them constantly in engagement with the ties.

What is claimed is:—

- 40 1. A railroad rail including an invertible and reversible body having upper and lower duplicate heads, and holding members for receiving the body therebetween and supporting the same, each of said members including a base, a rib extending downwardly therefrom, a flange upstanding from the base, the flanges and bases of the holding members coöperating to form a seat for the reception of the lower head of the body, and said flanges extending inwardly and upwardly against the lower faces of the upper head of the body.

45 2. A railroad rail including an invertible and reversible body having upper and lower duplicate heads, and holding members for receiving the body therebetween and supporting the same, each of said members including a base, a flange upstanding from the base, the flanges and bases of the holding members coöperating to form a seat for the reception of the lower head of the body, and said flanges extending inwardly and upwardly against the lower faces of the upper head of the body, there being a reinforcing rib 50 extending longitudinally under each

base plate in the line of thrust exerted by the upper head against the flange.

3. A railroad rail including an invertible and reversible body having upper and lower duplicate heads, and holding members for receiving the body therebetween and supporting the same, each of said members including a base, a rib extending downwardly from the base, a flange upstanding from the base, the flanges and bases of the holding members coöperating to form a seat for the reception of the lower head of the body, and said flanges extending inwardly and upwardly against the lower faces of the upper head of the body, there being interengaging portions upon the meeting faces of the body and flanges, for preventing longitudinal movement of the body relative to the flanges.

4. A railroad rail including an invertible and reversible body having upper and lower duplicate heads and a web connecting the same, and holding members, each of said members including a base, a rib extending downwardly from the base, and an upstanding flange extending longitudinally thereof, the bases and flanges of the two holding members coöperating to form a seat to fit snugly against and to receive the lower head of the body, the upper portions of the flanges bearing against the lower faces of the upper head of the body, and interengaging means upon the lower face of the upper head and the flanges for holding the body against longitudinal movement relative to the flanges.

5. A railroad rail including an invertible and reversible body having upper and lower duplicate heads and a web connecting the same, and holding members, each of said members including a base, a rib extending downwardly from the base and an upstanding flange extending longitudinally thereof, the bases and flanges of the two holding members coöperating to form a seat to fit snugly against and to receive the lower head of the body, the upper portions of the flanges bearing against the lower faces of the upper head of the body, teeth upon the lower faces of the upper head, and said flanges having toothed upper edges for engagement with the teeth.

6. The combination with invertible and reversible bodies having duplicate upper and lower heads and a web connecting the heads, said bodies having meeting ends, of holding members combined with the bodies and each including a base plate, a rib extending downwardly from the base and a longitudinal upstanding flange, said base plates and flanges coöperating to form a seat therebetween to receive and fit snugly against the lower heads of the bodies, said flanges converging upwardly and engaging the lower faces of the upper head of the rail, the holding members being extended

throughout the length of the bodies and past the ends thereof.

7. The combination with invertible and reversible bodies having duplicate upper and lower heads and a web connecting the heads, said bodies having meeting ends, of holding members combined with the bodies and each including a base plate, a rib extending downwardly from the base and a longitudinal upstanding flange, said base plates and flanges coöperating to form a seat therebetween and to receive and fit snugly against the lower heads of the bodies, said flanges converging upwardly and engaging the lower faces of the upper head of the rail, the holding members being extended throughout the length of the bodies and past the ends thereof, and means for fastening the bases to ties thereunder.

20 8. The combination with invertible and reversible bodies having duplicate upper and lower heads and a web connecting the

heads, said bodies having meeting ends, of holding members combined with the bodies and each including a base plate, and a longitudinal upstanding flange, said base plates and flanges coöperating to form a seat therebetween and to receive and fit snugly against the lower heads of the bodies, said flanges converging upwardly and engaging the lower faces of the upper head of the rail, the holding members being extended throughout the length of the bodies and past the ends thereof, there being a longitudinally extending reinforcing rib under each base plate for receiving the thrust exerted from the upper head through the flange.

In testimony that I claim the foregoing as my own, I have hereto affixed my signature in the presence of two witnesses.

FRANK O. HELLSTROM.
